UNITED STATES PATENT OFFICE.

FRANK HUBERT ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING-MACHINE.

1,387,959.

Specification of Letters Patent. Patented Aug. 16, 1921.

Application filed October 3, 1918. Serial No. 256,675.

To all whom it may concern:

Be it known that I, FRANK H. ARMSTRONG, a citizen of the United States of America, and a resident of Auburn, county of Cayuga, 5 State of New York, have invented certain new and useful Improvements in Typewriting-Machines, of which the following is a full and clear specification.

This invention has relation to that class 10 of case-shifts in which the case positions are obtained by shifting the type bar hanger or segment up and down, and the object of this invention is to improve and simplify this type of mechanism, as more fully hereinafter set forth.

In the drawings, Figure 1 is a perspective view of so much of a typewriting machine as is necessary to illustrate my invention, the near wall of the frame being broken 20 away;

Fig. 2 is a vertical sectional view showing the segment-carrier in its usual, *i. e.*, upper, position;

Fig. 3 is a similar view showing the segment-carrier in its middle position;

Fig. 4 is a similar view showing the segment-carrier in its lowest position;

Fig. 5 is a front elevation of the segment-carrier, the side members of the machine-frame being shown in vertical section;

Figs. 6, 7, 8 and 9 are detail views hereinafter fully described;

Figs. 10, 11 and 12 are views of a modification.

Referring to these drawings by reference-characters, 10 designates the segment-carrying-plate which is arranged adjacent to the rear wall of the frame and is adapted to carry the usual segment 11. This segment-carrying-plate is arranged to vertically slide on a pair of rods 12, one being arranged in each rear corner of the frame and each having its lower end rigidly connected to a forwardly-extending ear or flange 13 on the 45 rear wall of the frame and its upper end rigidly affixed to a forwardly-extending ear 14 integrally formed on the upper edge of the rear wall of the frame. The connection between each of these rods 12 and the segment-carrying-plate is by means of a pair of ears 15 formed integrally with the carrier-plate and projecting laterally therefrom, one at the upper edge of the plate and the other at the lower edge thereof,

each pair of these lugs being formed integrally with a forwardly-projecting flange 16 formed on the adjacent end of the segment-plate 10. The lugs 15 are provided with holes through which the rods 12 extend, the holes at one side of the machine being of a size to nicely fit the rod, but at the other side being elongated transversely of the machine to permit a slight play between the segment-carrier and the rod at that side of the machine, to thereby prevent binding of the segment-carrier on the rods in case the parts become slightly bent or twisted.

The segment-carrier is adapted to be pulled down to either its mid-position or its lower position by means of a pair of arms 17 whose forward ends are rigidly affixed to a rock-shaft 18 (journaled in the side walls of the frame and extending across the machine) and whose rear ends are pivotally and slidingly connected to the segment-plate by means of an open-ended slot formed in the rear end of each arm and engaging a headed-pin 19 affixed to the outer face of the adjacent one of the flanges 16. These arms 17, as will be observed, are arranged one at each side of the machine, and each arm is provided with an outwardly-extending lug or flange 20 whose upper, working face inclines downwardly and rearwardly.

The arms 17 are pulled downwardly, to thus cause the segment to descend, by means of shift-key-levers 21 and 22, these levers being, as usual, arranged in pairs adjacent the side-walls of the frame, each pair lying in a vertical plane between an arm 17 and the adjacent side wall of the frame. Each pair of shift-levers is pivotally mounted on a short bearing 23 extending inwardly from the adjacent side-wall of the frame and each lever is provided with an upwardly and forwardly-curved arm or tappet 24 so located and shaped that when the key-end of the lever is pressed downwardly this tappet will rock forward and downward and strike against the inclined upper face of the adjacent lug 20 and thus swing the arms 17 downwardly against the action of a coil-spring 25 whose lower end is connected to the lug or flange 20 and whose upper end is adjustably connected in any suitable manner to the adjacent side wall of the machine, this spring serving, as is obvious, to

normally hold the segment-carrier in its upper position. The tappet or arm 24 on the shift lever 22 is shorter than the tappet or arm 24 on the companion lever 21, so that depression of said lever 22 will, by reason of the shorter arc the working end of its tappet describes, depress the arms 17 a less distance than when the shift levers 21 are depressed, so that the shift lever 22 may be used for pulling the segment down to its mid-position while the companion lever 21 will be used for pulling the segment down to its third or lower position. Each of the shift levers is held in normal position by means of a suitable spring 26 and any suitable lock devices may be employed to lock either of the shift keys in its lower position to thus hold the segment in either of its two lower case positions. As a lock device, I prefer employing a swinging lever 27 pivotally mounted on the side wall of the frame and provided with a lateral lug 28 at its lower end which is adapted, when said lug 28 is swung forwardly, to engage a forwardly extending lug 29 on the shift lever, the engaging faces of these parts 28 and 29 being rounded or inclined with reference to each other so as to bring about a cam-like or wedging action between these parts.

In its upper case position, the segment-carrier abuts against a pair of depending screw-stops 30 carried by the lugs 14, and in its lower case-position it abuts against a pair of stop-screws 31 tapped up through the lugs 13 on the base of the frame, these two stop-screws being each provided with a suitable lock-nut to insure its being retained in its adjusted position. The segment-carrier is positively locked in its normal elevated position by means of a pair of upstanding arms 32 whose lower ends are affixed to a rock shaft 33 suitably journaled in the side walls of the frame and extending entirely across the frame, one of these arms 32 being arranged at each side of the machine, in position to be swung rearwardly to bring its upper end under the top lug 15 of the segment-carrier, said upper end being slightly inclined downwardly and rearwardly so that when it is swung rearwardly underneath said lug 15 it will cause a wedging or cam-like action and thus positively lock the segment against the screw-stops 30. Each of the lock-arms 32 is provided on its front edge with an inwardly-extending lug 34, each of these lugs lying in the path of upstanding cam portions or lugs 35 at the rear ends of the arms 36 of the two adjacent shift levers, said arms 36 extending upward and rearward from the fulcrum of the levers and the cam ends 35 thereof being so located as to ride upward behind lug 34 so that when either of the shift levers is depressed the cam lug 35 carried thereby will impinge against lug 34 and thus swing the lock-arms 32 forwardly far enough to disengage their upper ends from top lugs 15, thereby freeing the segment-carrier.

The front upper corners of the lugs 35 are beveled off to present downwardly-and-forwardly-inclined cam surfaces 37 for impingement against lug 34. The lug 35, which is a companion to the shorter arm or tappet 24 (being carried by the shift-lever 22) has a shorter beveled surface than lug 35 carried by shift lever 21, so that when shift lever 22 is operated, the lock-arms 32 will be thrown forwardly a less distance than when the companion shift-lever 21 is operated. When the lock-arms are thus shifted forwardly by means of the shorter beveled surface 37, these arms will be in position to bring lateral-stop-lugs 38 into vertical alinement with stop-screws 39 carried by the top lugs 15 of the segment-carrier to thus arrest the segment in its intermediate or "cap" shift position. When the segment is thus arrested, the stop-screws 39 will strike squarely on the upper faces of the stop-lugs 38 and these lugs will be located approximately in vertical alinement with the rock-shaft (33) which supports these lock-arms, so that the impact of the segment will be effectually taken care of. When this movement of the parts takes place, it will be observed that the finger-lug 35 will pass up behind the lug 34 and thus permit the shift-lever to be depressed far enough to bring the segment-carrier downwardly until its stop-screws 39 impact solidly against the stop-lugs 38. When the other shift-lever is depressed and the longer beveled surface 37 is brought into play, the lock-arms 32 will be swung far enough forwardly to permit the stop-screws 39 and their supporting ears 15 to pass down behind the stop-lugs 38, thereby permitting the segment-carrier to be depressed to its lowermost or "figure" shift position in which it will be arrested by the base stop-screws 31. The lock-arms 32 are normally swung rearwardly into locking position by means of coil-springs 40 connecting the extreme lower ends of these arms 32 at points below the rock-shaft to adjacent parts of the frame.

It will be observed that the cam surfaces 37 insure the rockable stop-frame being adjusted to the exact distance for the case-position selected, and it will be observed also that when the stop-frame is adjusted to the selected position by one or the other of the cam faces 37 it will be held forward in that adjusted position by the finger 35 engaging the lower corner or behind the lug 34. When the key-lever is released and allowed to ascend to normal position, the rockable frame is released from the finger 35 and its cam face 37, and spring 40 throws the rockable frame backwardly until the rear edges of its arms 32 strike against the front edges

of the top lugs 15 on the segment-carrier, where they rest until the segment-carrier is returned to its upper, normal, position, whereupon the upper ends of the arms 32 5 wedge under the aforesaid lugs 15 and thus lock the segment in its upper, usual, position.

It will be observed that when a shift-key is depressed, the segment-carrier will be 10 first unlocked by swinging the arms 32 forwardly; these arms continue to move forwardly until they reach the selected position, where they are arrested during the time the segment-carrier is descending to the selected 15 position. It will be further observed that a feature of importance in my construction is that the segment-carrier may be shifted downwardly from its intermediate or "cap" shift position to its lower or "figure" shift position without having to first return to normal 20 position; this is done by simply pressing down the other shift-key and thus bringing into action the longer one of the beveled or cam faces 37, which causes the rockable 25 arms to be swung farther forward to a position out of vertical alinement with the set screws 39, the shift-lever first used being released and thus permitted to return to normal position.

30 In the modified form of apparatus shown in Figs. 10, 11 and 12, the key-carrying arms of the shift-key levers are arranged above the arms 17, and flanges 20 are arranged to incline downwardly and forwardly so as to properly coöperate with the tappets or arms 24 which in the present instance depend from the key-carrying arms of the key-levers. The arms 36 of the key levers are curved forwardly and downwardly and their 35 cam edges 37 are arranged to face rearwardly and rest against the front edge of the lugs 34 on the rockable stop-frame, these lugs being located in this modified form at a point much lower down on the 40 rocking stop-frame and in front of its pivotal point 33. In operation, the segment-moving frame (which consists mainly of arms 17) is forced downwardly in the same manner as in the previously-described structure, and the cam edges 37 bear downwardly 45 and rearwardly against the front edge of lugs 34 and thus swing the rockable stop-frame forwardly to one position or the other according to which key-lever is used; and 50 when the stop-frame is moved to the selected position the lower edge of the end portion 55 of lever arm 36 slips over the top of lug 34 and thus locks the lock-frame in its adjusted position until the shift-lever is released.

60 The nature and scope of the invention having been thus indicated and its preferred embodiment having been specifically described, what is claimed as new is:

1. In a typewriting machine, the combination of a support shiftable to vary the relation

between printing instrumentalities and a platen, means for slidably holding the support to move vertically, a pair of rock arms extending fore and aft of the machine having a pivotal connection at their rear 70 ends with the support, a rock shaft forward of the support to which said rock arms are rigidly held, a pair of shift key levers pivotally supported to swing about a common axis at the rear of the rock shaft and provided with rock-arm depressing parts loosely 75 engaging one rock arm at points intermediate the rock shaft and the support, the rock-arm depressing part on one lever being longer than that on the other lever and engaging the rock arm at a point closer to the rock shaft than the other arm depressing part, and a spring for normally swinging the rear ends of the rock arms upward.

2. In a typewriting machine, a shiftable 85 segment-carrier, a pair of arms pivotally mounted at their forward ends and connected at their rear ends to said segment-carrier, one of the arms being provided with a downwardly - and - rearwardly - inclined 90 face, and a pair of shift levers provided with upwardly and forwardly extending parts of different length adapted to engage said inclined face to shift the arms different distances.

3. In a typewriting machine, a segment-carrier, means for normally holding it up, means for shifting the carrier downwardly embodying a pair of pivoted arms one of which carries a lateral lug facing upwardly, 100 and shift-key-levers carrying parts which when said levers are operated bear down on said upwardly facing lug.

4. In a typewriting machine, the combination of a support shiftable to vary the relation between printing instrumentalities and a platen, an arm extending fore and aft of the machine and pivotally supported in the machine frame at its forward end and pivotally connected at its rear end with the 105 support, means for guiding the support vertically, a spring for normally elevating the support, a laterally extending lug on said arm intermediate the ends of the arm, and a pair of shift key levers fulcrumed 110 in the machine frame at the rear of said lug and provided with parts of different length engaging the upper side of said lug at points spaced apart fore and aft of the machine.

5. In a typewriting machine, the combination of a support shiftable to vary the relation between printing instrumentalities and a platen, an arm extending fore and aft of the machine and pivotally supported in the 125 machine frame at its forward end and pivotally connected at its rear end with the support, means for guiding the support vertically, a spring for normally elevating the support, a laterally extending lug on 130

said arm intermediate the ends of the arm, and a pair of shift key levers fulcrumed in the machine frame at the rear of said lug, said levers extending under the lug and being provided with parts extending upwardly and forwardly over the lug and engaging the upper side of the lug at points spaced apart fore and aft of the machine.

6. In a typewriting machine, a movable segment-carrier, shift-key-operated devices for shifting the segment to its different case-positions, segment-stopping-and-locking devices automatically operated from said shift-keys, said stopping-and-locking devices embodying a pair of upstanding rockable arms, and means operable by the shift-keys for shifting these arms different distances, this latter means consisting of differentially-beveled members and cooperating devices on said arms.

7. In a typewriting machine, a shiftable segment-carrier, a pair of arms pivotally mounted at their forward ends and having their rear ends pivotally connected to said segment-carrier, each arm being provided with a laterally-extending member having a working face inclined downwardly and rearwardly, a spring for normally holding these arms in their upper position, a pair of shift-levers having different-length tappets arranged to engage said inclined surface to pull down the arm different distances, and stopping means for middle case-position automatically operated by said shift-levers.

8. Case shift mechanism for typewriting machines comprising a support shiftable to vary the relation between printing instrumentalities and a platen, a locking and shift-controlling member shiftably mounted independently of the support, means for normally moving said member into engagement with the support to lock the support in its normal position, key-operated means for shifting the support operatively connected with said member to shift the same out of locking engagement with the support to a position for arresting the support at a different point when said key-operated means is actuated.

9. Case shift mechanism for typewriting machines comprising a support shiftable to vary the relation between printing instrumentalities and a platen, a locking and shift-controlling member shiftably mounted independently of the support, means for normally moving said member into engagement with the support to lock the support in its normal position, a pair of shift keys connected with the support for shifting the same different distances, and connections between the keys and said member for shifting the member different distances from its locking position to determine the case-shift position to which the support is movable by each key.

10. In a typewriting machine, the combination of a vertically movable support for varying the relation between printing instrumentalities and a platen, means for arresting the support at its uppermost and lowermost positions, a shiftable stop for arresting the support in an intermediate position, and a pair of shift key levers connected with the support for shifting the same and having cam surfaces of different length for shifting the intermediate stop, the cam surface on one lever causing movement of the stop to operative position and the cam surface on the other lever causing movement of the stop to an inoperative position.

11. Double case shift mechanism for typewriting machines comprising a support shiftable different distances from a normal position to vary the relation between printing instrumentalities and a platen, means for normally moving the support in one direction, a pair of shift keys connected with the support for moving the support in the opposite direction, a shiftable member provided with an abutment for locking the support in normal position and an abutment for arresting the support in an intermediate position, and means whereby said member is shiftable a different distance by each key to release the support when either key is operated and render the abutment for arresting the support in intermediate position effective when one key is operated and ineffective when the other key is operated.

12. Double case shift mechanism for typewriting machines comprising a support shiftable to vary the relation between printing instrumentalities and a platen, means for normally moving the support upwardly, a swinging member mounted independently of the support for locking the support in its uppermost position and determining which of two lower positions the support may be shifted to, and a pair of shift keys connected with the support and said member for shifting the support downwardly and swinging said member different distances.

13. Double case shift mechanism for typewriting machines comprising a support shiftable different distances in the same direction to vary the relation between printing instrumentalities and a platen, a pair of shift keys connected with the support for shifting the same in one direction, a swinging member mounted independently of the support for engaging and locking the support in normal position and provided with an abutment adapted to arrest the support in its intermediate position, cam means operable by one of said keys for shifting said member out of locking position to a position in which said abutment will be effective to arrest the support, and cam means operable by the other key for shifting said

member out of locking position to a position in which said abutment will be ineffective.

14. Double case shift mechanism for typewriting machines, comprising a support 5 shiftable different distances to vary the relation between printing instrumentalities and a platen, a spring for normally moving the support in one direction, fixed means for determining the maximum limits of movement of the support, a swinging member 10 mounted independently of the support having an abutment for locking the support in normal position and an abutment for arresting the support in its intermediate position, a spring for normally swinging said member 15 to locking position, a pair of shift key levers having arms loosely engaging said member, and adapted to swing the same different distance from locking position, and connections 20 between the key levers and support for shifting the support.

15. Double case shift mechanism for typewriting machines, comprising a support shiftable different distances to vary the relation between printing instrumentalities and a platen, a spring for normally moving the support in one direction, fixed means for determining the maximum limits of movement of the support, a swinging member 25 mounted independently of the support having an abutment for locking the support in normal position and an abutment for arresting the support in its intermediate position, a spring for normally swinging said member 30 to locking position, and a pair of shift key levers each having an arm connected with said member and an arm connected with the support and also a key-carrying arm, the arms on said levers connected with said 35 member being adapted to swing the member different distances from locking position.

16. In a typewriting machine, the combination of a machine frame, a support shiftable vertically in the frame to change case, 40 means for normally moving the support upwardly, fixed means on the frame coöperating with the support to arrest the support in its uppermost and lowermost positions, a rockable member mounted on the frame for 45 locking the support in its normal uppermost position, a stop on said member adapted to arrest the support in a central position, a pair of shift key levers provided with arms of different length for shifting the support downwardly different distances and arms for shifting said rockable member different distances from locking position.

17. In a typewriting machine, the combination of a machine frame, a pair of vertical 50 guide posts rigidly held in the rear part of the frame adjacent opposite sides of the frame, a plate extending transversely of the frame and provided with horizontal ears adjacent its upper and lower edges at each end 55 thereof through which said rods extend, ver-

tically spaced stationary stops on the frame adapted to be engaged by the upper and lower ears to determine the upper and lower positions of the plate, a type-bar segment held to the front face of the plate, a rock 70 shaft journaled in the frame forward of the plate, a pair of rearwardly extending rock arms held to said shaft and pivotally connected with the plate, a pair of upstanding rocking members mounted in the frame 75 at opposite sides thereof to swing in unison fore and aft of the machine and each provided with a pair of stepped abutments adapted to coöperate with one of the upper ears on the plate to respectively lock the 80 plate in its upper position and arrest the plate in its central position, and a pair of shift levers at one side of the machine connected with the adjacent rock arm for lowering the plate and connected with the adjacent rocking member for releasing the plate when either lever is operated and positioning said members to arrest the plate in central position when one of the levers is operated.

18. In a typewriting machine, the combination of a frame, a support shiftable vertically in the frame to change case, a rock shaft journaled in the frame, a pair of rock arms held to said shaft at their forward ends 90 and pivotally connected at their rear ends with the support, means for guiding the support, a spring for normally moving the support upward, a pair of key levers fulcrumed in the frame at a point in the rear of the 95 rock shaft and having parts loosely engaging one of the rock arms different distances from the rock shaft, a member mounted in the frame to swing fore and aft of the machine and provided with an abutment 100 adapted to engage the support to lock the support in its normal elevated position and an abutment adapted to arrest the support in an intermediate position, and a stationary 105 stop on the frame for arresting the support in its lowest position, said key levers being provided with parts for swinging said member different distances from locking position.

19. Double case shift mechanism for typewriting machines comprising a support shiftable to change case, means for guiding the support to move up and down, stationary means coöperating with the support to arrest the support in its uppermost and 110 lowermost positions, a rocking member mounted independently of the support and movable to three different positions in one of which it locks the support in its uppermost position, means for normally moving the support upwardly, means for normally 115 rocking said member to locking position, a pair of shift keys connected with the support for shifting the same downward, cam means controlled by one key for rocking 120

said member to a position for arresting the support in its intermediate position, and cam means controlled by the other key for rocking said member to a position permitting movement of the support to its lowermost position.

20. In a typewriting machine, the combination of a frame, a pair of vertical guide posts in the frame adjacent opposite sides thereof, a type-bar hanger support slidably held to said posts, a transverse rock shaft journaled in the frame adjacent said posts, a pair of upstanding rock arms held to said shaft adjacent opposite ends of the support, means for limiting the extent of movement of the support on said posts, means for normally moving the support upward,

means on the support adjacent each end thereof coöperating with the rock arms for locking the support in its uppermost position and arresting the support in a position intermediate the limits of its movement, means for normally swinging the rock arms to support-locking position, a shift key connected to move the support downward and 25 position the rock arms to arrest the support in its intermediate position, and a shift key connected to move the support downward to its lowermost position and move the rock arms to an inactive position. 30

This specification signed this 10th day of September, A. D. 1918.

FRANK HURBERT ARMSTRONG.
